REFRIGERATION

Albert R. Thomas, Evansville, Ind., assignor to
 Servel, Inc., New York, N. Y., a corporation of
 Delaware

Application May 6, 1941, Serial No. 392,090

4 Claims. (Cl. 261—112)

My invention relates to cooling towers, and more particularly to cooling towers of the induced draft type in which liquid flowing downward by gravity is cooled by partial evaporation into air flowing countercurrent to the liquid.

It is an object of my invention to provide an improved cooling tower in which air passes countercurrent to downwardly flowing liquid at a relatively high velocity with substantially no entrainment of liquid in the air stream, so that the necessity of providing eliminators or similar devices to effect removal of liquid from the air stream is avoided.

Another object of the invention is to provide an improved cooling tower of the induced draft type in which counter-current flow of air and liquid is effected with air velocities as high as 1,000 feet per minute, so that a cooling tower of a given capacity will occupy a relatively small amount of space.

A further object of the invention is to provide an improved cooling tower in which the liquid to be cooled is distributed in a region or pocket not directly in the high velocity air stream to cause liquid films to be formed on suitable vertically extending surfaces contacted by the air stream.

A still further object of the invention is to provide an improved cooling tower utilizing countercurrent flow of air and liquid to effect cooling of the liquid, and to spray the liquid onto the top edges of paneling at a region in which the air is relatively stagnant to produce liquid films adapted to be contacted by air flowing at a high velocity.

The novel features which I believe to be characteristic of my invention are set forth with particularity in the claims. The invention, both as to organization and method, together with the above and other objects and advantages thereof, will be better understood by reference to the following description taken in connection with the accompanying drawings, and of which:

Fig. 1 is a view more or less diagrammatically illustrating a cooling tower embodying the invention shown in connection with an absorption type refrigeration system;

Fig. 2 is a perspective view of the cooling tower shown in Fig. 1;

Fig. 3 is an enlarged vertical sectional view, taken on line 3—3 of Fig. 2, to illustrate parts of the cooling tower more clearly;

Fig. 4 is an enlarged fragmentary sectional view, taken at line 4—4 of Fig. 3, to illustrate

the manner in which liquid films are formed on the paneling;

Fig. 5 is an enlarged fragmentary sectional view, taken on line 5—5 of Fig. 3; and

5 Figs. 6 and 7 are fragmentary perspective views illustrating in detail the paneling shown in Figs. 3 and 4.

Referring to Fig. 1, the improved cooling tower 10 embodying my invention is shown in connection with an absorption type refrigeration apparatus 11. In apparatus of this type liquid refrigerant evaporates in a cooling unit with consequent absorption of heat from the surroundings to produce a refrigerating effect. 10 The refrigerant vapor formed in the cooling unit is absorbed into a liquid absorbent in an absorber 12 and absorption liquid, enriched in refrigerant, is conducted to a generator. By heating the generator, refrigerant is expelled from the absorption liquid, liquefied in a condenser 14, and then returned to the cooling unit to complete the refrigerating cycle. In order to simplify the drawings, the refrigeration apparatus 11 has been illustrated very generally and in outline with the absorber 12 and condenser 14 constituting the only parts specifically shown, the remaining parts of the apparatus not being illustrated since this is not believed to be necessary for an understanding of my invention.

30 The heat of absorption resulting from absorption of refrigerant vapor in absorber 12 is given up to a suitable cooling liquid, such as water, which enters the absorber through a conduit 15. The cooling water is conducted from absorber 12 through a conduit 16 to condenser 14 in which heat of condensation, resulting from condensation of refrigerant vapor, is given up to the cooling water. From the condenser 14 the cooling water is conducted through a conduit 17 to cooling tower 10, and, after being cooled in the latter, the cooling water flows through conduit 15 to absorber 12 to complete the cooling water cycle.

45 Referring more particularly to Figs. 1, 2 and 3, the cooling tower 10 includes a base 18, an upright shell 19 mounted on and extending upward from the base 18, and a hood or cover 20. The base 18 is formed with inclined side walls 21 having air inlet openings 22 which are covered by screens 23. One of the side walls of shell 19 is provided with an opening at the upper part thereof to which is connected an L-shaped duct 24 having an upper exhaust opening or outlet 50 covered by a screen 26.

Within duct 24 is provided a blower or fan 27 connected by a belt 28 to an electric motor 29 adapted to be connected to a suitable source of electrical energy. The motor 29 is disposed in a casing 30 supported at the bottom of the horizontal portion of duct 24, and, in order to dampen the vibrations of the motor 29, the latter is preferably mounted on rubber blocks, as indicated at 31 in Fig. 3.

When fan 27 is operating, air is drawn into the base 18 through the inlets 22 and flows upward through shell 19. The side wall of shell 19 to which duct 24 is connected is provided with a deflector or baffle 32 to increase the vertical distance through which air flows upwardly in shell 19, and also to cause the air to pass into the top part of the horizontal portion of duct 24. From duct 24 the air is discharged at the outlet 25 to the atmosphere. The screens 23 at the inlets 22 remove foreign matter from air drawn into the base 18, and the screen 26 at the outlet 25 protects the fan 27 disposed in the duct 24.

The cooling water conducted through conduit 17 to the top part of cooling tower 10 is distributed within the hood or cover 20 and flows downward by gravity in shell 19 in a manner to be described presently. During downward flow in shell 19, the water is cooled by partial evaporation into the air stream flowing countercurrent thereto. The cooled water collects in the bottom part of base 18 which serves as a sump. To the base 18 is connected a conduit 33 through which water is conducted from a suitable source of supply. The water is maintained at a predetermined level in the bottom of base 18 by a float 34 operatively connected by an arm 35 to a valve 36 which is connected in the part of conduit 33 within the base 18.

During circulation of water in the cooling water circuit described above, a small amount of water is lost due to evaporation in the cooling tower 10. The water conducted to base 18 through conduit 33 keeps the water at a predetermined level in the sump and is referred to as additional or make-up water which takes the place of water lost by evaporation. An overflow conduit 37 is located in the bottom part of base 18 so that water can flow to waste when the liquid level in the sump rises above the upper end of this conduit.

The water is drawn from the bottom of base 18 through suitable screening 38 connected to the end of conduit 15, so that foreign matter will be removed from the water prior to entering the absorber 12 and condenser 14. A pump 39, which is connected in conduit 15 and arranged to be driven in any suitable manner, as by an electric motor, for example, is provided to circulate the cooling water through absorber 12 and condenser 14 of the refrigeration apparatus 11.

Within the upright shell 19 are disposed a plurality of closely spaced vertical panels 40. The panels 40 are held in position by suitable supporting structure including a plurality of horizontal angle members 41 having the ends thereof secured to the end walls of base 18, as indicated at 42 in Fig. 3. The horizontal angle members 41 are located at the same height and are parallel to each other with each member being disposed adjacent to and substantially midway between the top and bottom edges of the inlets 22. To the horizontal angle members 41 are secured the lower ends of a plurality of U-shaped channels or guides 43, as shown most clearly in Figs. 75

3 and 5. The channels 43 are spaced close together at opposite sidewalls of shell 19 with the open ends facing each other. The rear sides of the closed ends of channels 43 are secured to horizontal angle members 44 having the ends thereof connected to the end walls of shell 19. The horizontal angle members 44 are positioned at the extreme upper ends and also at a central or intermediate region of the vertical channels 43 to provide a rigid supporting structure for the panels 40 now to be described more fully. A suitable reinforcing member 45 extends from one sloping sidewall 21 to the opposite sidewall of base 18 and is connected at its ends to intermediate regions of the horizontal angle members 44, as best shown in Fig. 3.

The panels 40 are preferably formed from a number of separate plates 46 disposed one above the other. The plates 46 may be formed of wood or metal, and plates formed from red cypress have been satisfactorily employed. The vertical channels 43 at opposite sides of shell 19 are directly opposite each other and receive the plates 46. The bottom plates 46 of each panel 40 rest directly against the bottom horizontal angle members 44. From the base 18 to the region of shell 19 just below the top edge of deflector 32, the plates 46 in each panel 40 preferably do not abut each other but are spaced apart by approximately one-half inch by spacer rods 47 which are parallel to the sidewalls and extend from one end wall to the opposite end wall of shell 19. The spacer rods 47 rest against the open ends of vertical channels 43 with each rod being held in position by the weight of the plates 46 and rods 47 above it. In the top part of shell 19, at the region extending upward from the extreme top edge of deflector 32, the plates 46 rest directly against each other to form solid panel portions, as best shown in Figs. 3 and 4.

The hood or cover 20 is removably fastened to the top part of shell 19, as indicated at 48 in Figs. 2 and 3. Within hood 20 is secured a pipe 49 which serves as a manifold for distributing water and to which is connected a plurality of spray heads or nozzles 50. One end of the pipe 49 is closed and the other end thereof is open and passes through a wall in the hood 20, as shown in Fig. 4. To the part of pipe 49 extending outside the hood 20 is connected the lower end of conduit 17. In order that the hood 20 can be readily removed during operation of the cooling tower, the lower portion of conduit 17 is preferably flexible.

The water conducted through conduit 17 to the nozzles 50 is sprayed in the pocket or chamber 51 formed by the hood 20. In order to form water films on the panels 40 the top plates 46 of each panel are provided with water distributing slats 52. The slats 52 are of the shape shown in Figs. 4 and 6 and are formed with tapered top portions to provide sloping surfaces for conducting spray water toward the surfaces of the highest plates 46. The slats 52 are secured to the top plates 46 in any suitable manner, as indicated at 53 in Fig. 6. The slats 52 are formed with slots 54 to provide narrow passages at the surfaces of plates 46 to facilitate the formation of the liquid films on the surfaces of the panels 40.

During operation of the cooling tower 10, the water returning from the refrigeration apparatus 11 is sprayed into the chamber 51 by the nozzles 50, as described above. It is only necessary to deliver water to the nozzles 50 at a relatively

low pressure which is just sufficient to cause distribution of the water over the entire top edges of the panels 40. In practice it has been found that delivering the water to the nozzles 50 at a pressure as low as two or three pounds per square inch is adequate to produce satisfactory distribution of the water in chamber 51.

The tapered sides of the slats 52 and adjacent surfaces of the uppermost plates 46 form troughs 55, as best shown in Fig. 4, in which water collects. The water collecting in the troughs 55 is formed by the drops of spray water falling onto the top edges of the uppermost plates 46 and sloping sides of the slats 52. The water in troughs 55 passes between the contacting surfaces of the slats and portions of plates 46 covered by the slats, and also around the ends of the slats and through the passages formed by the slots 54, to produce liquid films on all of the surfaces of the uppermost plates 46. The water films first flow continuously on the solid upper portions of the panels 40.

At the region just below the top edge of the deflector 32, the first gaps 56 are formed in the panels by the uppermost spacer rods 47, as shown most clearly in Fig. 3. The gaps 56 are provided in the panels 40 to cause the water to drip from the bottom edge of each plate 46 onto the top edge of the succeeding lower plate to facilitate and promote the spreading of the water on the plates 46, so that the surfaces of the panels 40 are completely wetted and the tendency for water films to form distinct streams will be avoided.

From the bottom edge of the lowermost plates 46 the water falls onto a splash plate 57 disposed in the base 18. The plate 57 is provided with inclined surfaces which are in the paths of the falling drops of liquid and extend below the water level in the base 18. With this arrangement the water flows on the inclined surfaces of the plate 57 and eliminates the noise in splashing that is usually encountered when drops of water fall onto the flat surface of a body of water.

The air drawn into the cooling tower 10 through the inlets 22 flows into the passages between the panels 40 not only at the bottom edges of the panels but also along the portions of the end edges thereof which project downward into the base 18 from the bottom of shell 19. The air flowing upward in shell 19 in the narrow passages between the panels 40 acquires a high velocity and comes in contact with the films of water formed on the surfaces of the plates 46. The water flowing downward by gravity on the surfaces of the plates 46 is cooled by partial evaporation into the upwardly flowing air. The air stream changes direction very abruptly at the top part of shell 19 with the air stream making practically a 90° or right angle turn from shell 19 into duct 24.

It will be seen that the distribution of water onto the top edges of panels 40 is effected in chamber 51 which forms a dead-end pocket in the top part of the cooling tower with respect to the upwardly flowing air stream. The uppermost plates 46 and slats 52 associated therewith constitute a barrier to flow of air into dead-end pocket 51 in which the air is relatively stagnant. In this way the distribution of water onto the panels 40 is effected in a region not directly in the high velocity air stream flowing upward in shell 19 and passing into duct 24, as indicated by the arrows in Fig. 3. In the part of shell 19 in which the high velocity air stream is pass-

ing, the air comes in contact with the films of water which flow downward on and cling to the surfaces of the panels 40. The slats 52 insure the formation of the water films on the panels 40, so that drops of water from chamber 51 will not fall between the panels 40 into the air passages.

Below the top edge of the deflector 32 drops of water fall in the gaps 56 from the bottom edges of the plates 46 onto the top edges of the succeeding lower plates. These drops of water fall in regions at one side of streams of air passing upward at a relatively high velocity between the panels 40. The water dripping in the gaps 56 is protected to a great extent from the air flowing past the gaps from each plate 46 to the succeeding higher plate. At the gaps 56 there is a tendency for the pressure at these regions to be reduced slightly due to the action of the high velocity air passing these regions, whereby a pulling effect is exerted on the drops of falling water. Since the pulling effect on the water drops at one side of the gaps 56 is counteracted by a similar pulling effect on these drops at the opposite sides of the gaps, the drops of water in the gaps 56 tend to remain in these regions and fall onto the top edges of the plates 46. Hence, entrainment of the drops of water in gaps 56 by upwardly moving air is not readily effected.

At the upper region of shell 19 at which the air stream makes an abrupt 90° or right angle turn, the panels 40 are solid with no gaps provided between the individual plates 46. The solid portions of the panels 40 provide continuous surfaces to which the water effectively clings, so that entrainment of such water into the air stream is effectively prevented. Moreover, any tendency for water to be entrained in the upwardly air flowing in shell 19 is effectively counteracted by the abrupt change in direction of air flowing from the shell into the duct 24.

The water dripping from the bottom edges of panels 40 onto the splash plate 57 does not come into contact with high velocity air, because the air velocity does not build up until the air flows into the narrow passages formed between the panels 40. Hence, there is substantially no entrainment of water by the air while the latter is passing through the upper part of base 18. Any tendency for water to be entrained in the air in base 18 is effectively counteracted by causing the air stream to make an abrupt 90° or right angle turn upwardly into shell 19 after entering the base 18 more or less horizontally through the inlets 22.

In the cooling tower 10 it is possible to flow air counter-current to the water at velocities considerably greater than heretofore possible. The ability to cause circulation of air through the cooling tower at relatively high velocities is due primarily to spraying the water in the pocket or chamber 51 in which the air is relatively stagnant, and flowing the water directly onto the surfaces of the panels 40 in the dead end pocket. With this arrangement, as pointed out above, when the water comes into contact with the upwardly flowing air stream, films of water are produced on the surfaces of the panels 40 to which the water readily clings. By flowing air counter-current to films of water in the manner described, it is possible to effect cooling of water with their velocities as high as 1,000 feet per minute, whereby a cooling tower of a given ca-

pacity will occupy a relatively small amount of space.

While a single embodiment of the invention has been shown and described, it will be apparent to those skilled in the art that modifications and changes may be made without departing from the spirit and scope of the invention, as pointed out in the following claims.

What is claimed is:

1. A cooling tower comprising a casing providing an upright shaft having an inlet for air in the lower part thereof and an outlet for air at the upper part thereof, members in said passage providing liquid bearing surfaces projecting above said air outlet, liquid distribution structure for depositing liquid on said surfaces and forming a liquid film thereon in a zone above said air outlet, said structure including a barrier to flow of air between the zone in which liquid is deposited on said surfaces and said air outlet, said liquid bearing surfaces being substantially continuous in vertical extent in the region of said air outlet so that all the liquid descending by gravity through this region is adherent to said members so as not to be entrained by air flowing from the passage at high velocity, and said surfaces having small gaps at places below said air outlet so that liquid is redistributed on said surfaces by dripping across said gaps, the spacing between said members being proportioned so that the velocity of air is substantially the same on all sides of said gaps so that the

dripping liquid is not displaced into the air streams.

5 2. A cooling tower as set forth in claim 1 in which said liquid distributing structure includes a spray device within a hood or cover removably attached to said casing over the upper end of said shaft.

10 3. A cooling tower as in claim 1 in which said members are formed of spaced apart vertically extending slats, and said liquid distributing structure includes a sprayer over the upper ends of said slats, and said barrier is formed of closure members between adjacent slats, said closure members having drain openings adjacent the surfaces of the slats.

15 4. A cooling tower having a liquid inlet at the top, a filler comprising spaced apart vertically extending slats, connections for flow of air upward through said tower, and a partition at the upper end of said slats below said liquid inlet formed by a plurality of closure members secured between adjacent slats at their upper ends to fill the gaps between said slats, said closure members having grooves in their edges next to the surfaces of said slats so that water deposited upon the top of said partition is divided by said closure members and flows downward through said grooves at the opposite edges of said closure members on to the opposing surfaces 20 of each pair of adjacent slats.
